UNITED STATES PATENT OFFICE.

WILLIAM W. WALLACE, OF CHICAGO, ILLINOIS, ASSIGNOR TO NEW YORK BRICK HANDLING CORPORATION, OF NEW YORK, N. Y., A CORPORATION OF NEW YORK.

DUMPING FORK.

Application filed March 30, 1925. Serial No. 18,213.

To all whom it may concern:

Be it known that I, WILLIAM W. WALLACE, a citizen of the United States, and a resident of Chicago, in the county of Cook and State of Illinois, have invented an Improvement in Dumping Forks, of which the following description, in connection with the accompanying drawings, is a specification, like reference characters on the drawings representing like parts.

My present invention relates to lifting devices, and more particularly to an improved truck loading and dumping fork for use in connection with the handling of brick.

The present invention is an improvement over prior apparatus of this class such as R. C. Penfield Patent No. 1,265,106, granted May 7, 1918, and improved apparatus disclosed in my Patent No. 1,474,806 dated Nov. 20, 1923. In prior apparatus it has been impractical to utilize mechanical brick lifting devices to remove the brick from the kiln after the burning operation, such brick being more advantageously removed in stacks or units. This difficulty is caused by the fact that the rows or courses of brick in a kiln shrink unevenly and vary in their horizontal alignment. Not only does each course of brick shrink in a somewhat different manner from those adjacent to it, when burned, but such variation is apt to be distorted throughout the plurality of courses. Consequently the rows of brick in a kiln, after a kiln is burned, are in a wave-like formation, the distortion being mostly in a horizontal plane. Because of this fact, it has been impossible to utilize a setting device with brick engaging fingers in alignment as a line of brick itself was distorted and never in alignment after the brick are burned. In my prior patent above referred to, the utilization of a brick lifting fork in the situation outlined is accomplished by providing independently movable fingers which will follow the variation in the line of the bottom courses of the brick in the stack or pile, thus gradually bringing such bottom courses into alignment. In my present invention, however, I have accomplished practically the same result and am enabled to make a more rigid fork than that described and claimed in my patent above referred to, and do this by providing a fork, the fingers of which are extremely

narrow sided, this structure enabling me to force the fork in between the rows forming the bottom course of bricks in a unit stack or pile. By means of this structure I am enabled to make a device that is more easily and solidly locked in the brick lifting position and which may be readily released from such locking position, the plurality of teeth forming the lifting element being secured to a pivotally mounted member so that the plurality of teeth rotate in unison to discharge the load of brick from the fork.

The principal object of my invention, therefore, is an improved brick lifting and dumping fork.

Another object of my invention is an improved means for pivotally attaching the brick lifting fingers in a combined lifting and dumping fork.

Other objects and novel features of the construction and arrangement of parts comprising my invention will appear as the description of the invention progresses.

In the accompanying drawings illustrating the preferred embodiment of my invention,

Fig. 1 is a front elevation;

Fig. 2 is a side elevation;

Fig. 3 is a horizontal section, taken on the line 3—3 of Fig. 2, and

Fig. 4 is a sectional side elevation on the line 4—4 of Fig. 3.

My improved fork can be used either with or without the dumping feature, but is explained herein as comprising both capabilities.

Referring to the drawings, 10 designates a plate of any suitable length and width to which is riveted at the forward upper end 95 an angle 11. Secured to the front edge of the plate 10 and the front face of the angle 11 by brackets 12 are hanger bars 13, these bars extending upward and converging at a point any suitable distance above the plate 10, as clearly shown in Fig. 1. Secured to the upper ends of the hanger bars 13 by riveting, or in any other suitable manner, are cantilever bars 14. There are two of the cantilever bars symmetrically arranged with respect to the length of the plate 10 and angle 11, as clearly shown in Fig. 1, and said cantilever bars extend rearwardly and forwardly from the hanger bars 13. To the rearward end of the cantilever bars 110

are secured, as by riveting, back braces 15, and these braces extending rearwardly and downwardly, as shown in Fig. 2. Along the rear upper edge of the plate 10 is secured 5 an angle 16 lying parallel to the angle 11, and secured to the angle 16 by brackets 17 are the lower ends of the back braces 15. Pivotally attached to the forward and rearward ends of the cantilever bars 14 are 10 suspending links 18, these links being utilized to suspend the loading fork from a crane or other lifting device. Extending between the cantilever bars 14 at the point of connection of the hanger bars 13 therewith 15 is a tie rod 19, such rod being secured in position by the nuts 20. Secured to the front edge of the hanger bars 13 on brackets 21 is a front plate 22, the upper end of which extends upwardly and rearwardly, as shown 20 in Figs. 2 and 4, such upper end being slotted to receive the hanger bars. The hanger bars 13 extend downward to a point below the lower edge of the front plate 22, such lower ends being provided with 25 perforations in alignment with each other to receive hinge bars, as will be hereinafter described.

Numeral 23 designates a finger spacer and hinge weight, this spacer and weight being 30 provided with a plurality of vertically arranged and equally spaced slots in each of which is adapted to fit the fingers 24. These fingers are in the shape of an angle, as shown in Figs. 2 and 4, the forwardly extending portion being the lifting portion and on which the load may rest, while the vertically arranged portion fits snugly into the slots referred to as being in the finger spacer and hinge weight. When the fingers are in 35 position in the slots, a finger clamp 25 is secured to the front face of the finger spacer and hinge weight by means of bolts 26 that extend through the finger spacer and hinge weight and are provided with nuts 27 on their rear ends. The fingers 24 and finger spacer 23 are drilled to receive hinge bars or rods 28 from either end of the lifter, such hinge bars or rods being threaded at 40 their inner end and screw into a hinge bar nut 29, as clearly shown in Fig. 1.

Secured to the under face of the plate 10 at the rear thereof and on each side of the center thereof, or substantially in alignment with the back braces 15, are latch shaft bearings 55 30 and in such bearings is rotatably mounted a shaft 31. Secured to the shaft 31 at each of the latch shaft bearings 30 is a locking dog 32. Secured to the top rear surface of the finger spacer and hinge weight 60 23 by bolts 34 are locking plates 35, the upper rear portion of which is hardened to reduce wear. The locking dog is notched to engage with said locking plate 35 and is adapted to hold the finger spacer 23 and 65 attached fingers 24 in the position shown in

full lines in Fig. 4. When, however, the shaft 31 is rotated in a clockwise direction, as viewed in said Fig. 4, the latch 32 is withdrawn from engagement with the locking plate 35 and the finger spacer with attached fingers 24 moves into the position shown in dotted lines in said Fig. 4. Secured to the shaft 31 intermediate its ends, or substantially midway between the latch shaft bearings 30, is a trip lever 36, the 70 handle of which extends rearwardly to any desired distance, and secured to the free end of such trip lever handle is a lanyard 37 and by means of which the same may be operated to trip the finger spacer 23 and 75 attached parts. Formed integral with the trip lever 36 is an upwardly and forwardly extending arm 38, the upper end of which engages with the under face of the plate 10 to limit the rotative movement in an anti-clockwise direction of the shaft 31. Adjacent to the upper end of the portion 38 is provided a perforation in which is secured one end of a spring 39, the other end of this spring being attached to a spring lug 40 80 secured to the angle 16 by bolt 41. The suspension links 18, as above described, are utilized to suspend the device from a crane, or similar structure, and the suspending 85 points are such that the fork is held by a four point suspension; that is, the fingers 24 are held in their operative position, as shown in Fig. 2, and in full lines in Fig. 4, horizontal.

The operation of my device is as follows, 100 assuming that the device has been constructed as above described and that it is desired to load a truck with brick, the brick being taken directly from a kiln and in unit loads, the units being of any desired size and preferably within the capacity of the lifting and dumping fork. It should be noted at this point that the unbalanced weight of the finger spacer 23 is sufficient to cause a 105 rotation thereof and of the attached fingers 24 into the full line position shown in Fig. 4 where the locking dogs 32 engage with the locking plates 35. The crane is now operated to move the loading and dumping fork into position to engage with the under portion of a unit stack of brick in a kiln, the fingers 24 sliding in between the bottom courses of such unit stack. When in position, the crane is operated to lift the loading and dumping fork and the load of brick 110 120 carried to any point desired as, for example, above the body of a truck. When the dumping fork is in proper position, the operator pulls on the lanyard 37, rotating the shaft 31 and moving the locking dogs 32 out of 125 engagement with the locking plates 35 when the weight of the unit stack of brick will rotate the finger spacer 23 and fingers 24 from the full line position shown in Fig. 4 to the dotted position shown in such figure. 130

My improved loading and dumping fork is simple in construction, easily and accurately operated, and being composed of relatively few parts, is not liable to derangement.

While I have necessarily described my improved device somewhat in detail, it is to be understood that I may vary the size, shape, and arrangement of parts within reasonably wide limits without departing from the spirit of the invention. By using the improved fork as a distinct lifting and loading or unloading apparatus the same can be utilized substantially as shown in the 10 said prior patent of R. C. Penfield, particularly when transferring brick from a kiln or stack into a car, wagon, or other device and when it is desired to maintain the brick substantially in stacked units. The fork 15 will operate with the individually movable fingers rigidly extended, until the operator desires to pull the lanyard to release the same. Thus my present improved brick handling apparatus can be used to great 20 advantage either as a means of transferring a mass, unit or pile of brick while maintained in their stacked or hacked relation, or as a quick dumping and releasing device 25 to take the brick from the kiln or stack, and

dump them into a wagon or other receptacle 30 or loose pile.

Having thus described my invention, what I claim as new is:

1. In an improved loading and dumping fork, the combination of a body portion, a 35 finger spacer and hinge weight pivotally mounted at the lower front end thereof, a plurality of parallelly arranged fingers secured to said finger spacer and hinge weight, the unbalanced weight of the finger spacer and hinge weight on its pivot being greater than the unbalanced weight of the parallelly arranged fingers on such pivot whereby the finger spacer and hinge weight tend to rotate about the pivot, means for limiting the 40 rotative movement thereof, and means for holding said finger spacer and hinge weight against reverse rotation.

2. An improved brick handling fork, comprising a plurality of horizontal extending members adapted to be disaligned for loading brick thereon, means to maintain said horizontal members thus positioned, or to instantly shift same to an unloading angle to slide off the brick contained thereon.

In testimony whereof, I have signed my name to this specification.

WILLIAM W. WALLACE.
